UNITED STATES PATENT OFFICE.

HARRY B. JACKSON, OF SHARPSBURG, PENNSYLVANIA.

EMERGENCY COUPLING-LINK.

1,290,209.

Specification of Letters Patent.

Patented Jan. 7, 1919.

Application filed February 14, 1918. Serial No. 217,168.

To all whom it may concern:

Be it known that I, HARRY B. JACKSON, a citizen of the United States of America, residing at Sharpsburg, in the county of Allegheny and State of Pennsylvania, have invented certain new and useful Improvements in Emergency Coupling-Links, of which the following is a specification.

This invention relates to emergency coupling links and has for its object to provide, in a manner as hereinafter set forth, a link capable of being quickly and conveniently positioned to couple together the lengths of a broken tread chain across a tire, to enable the further use of the chain, and to overcome the possibility of the broken lengths injuring the tire, and also the necessity of discarding the broken lengths under such conditions providing a saving in expense.

Further objects of the invention are to provide a link for the purpose set forth which is simple in its construction and arrangement, strong, durable, efficient in its use, readily attached in position, and inexpensive to manufacture.

With the foregoing and other objects in view the invention consists of the novel construction, combination and arrangement of parts as hereinafter more specifically described and illustrated in the accompanying drawing, wherein is shown an embodiment of the invention, but it is to be understood that changes, variations and modifications can be resorted to which come within the scope of the claim hereunto appended.

In the drawings wherein like reference characters denote corresponding parts throughout the several views:

Figure 1 is an elevation of a portion of a chain illustrating a link in accordance with this invention attached thereto and open.

Fig. 2 is a like view with the link closed.

Fig. 3 is an elevation of the link.

Referring to the drawings in detail 1 and 2, denote links of lengths of a broken tread chain, which as illustrated in Fig. 2, are connected together by a coupling-link, in accordance with this invention.

The coupling-link is formed from a single length of material of the desired thickness, and consists of a straight uninterrupted side portion 3 which terminates in a pair of arcuate end portions 4, 5, the latter being ma-

terially smaller than the former. The end 4, terminates in a stem 6, which is disposed at 55 an inclination and prior to the closing of the link is disposed at an acute-angle, but when the link is closed extends at an obtuse-angle.

The end 5, terminates in an inclined stem 60 7, which is of greater length than the stem 6, and which extends at an acute-angle when the link is open, or when the link is closed, the angle being greater when the link is closed.

When the link is closed, that side of the link opposite the side 3, and which is indicated at 8, is disposed at an inclination with respect to the side 3, and is formed by the stems 6, 7, but said side 8 is interrupted, due 70 to the fact that the stems 6, 7, do not abut. When the side 8, is formed by the stems 6, 7, the ends of these latter oppose each other.

The length of the stem 7, with respect to the length of the stem 6, is such that when 75 the side 8, is formed the stem 7, does not overlap the stem 6:

The coupling-link when open can be conveniently positioned due to the inclined stems 6, 7, with respect to the links of the 80 lengths of the broken chains, and the stems can be bent so as to close the coupling-link, whereby the lengths will be connected together and the tread chain utilized for the purpose for which it is intended.

What I claim is:

An emergency coupling-link for the lengths of a broken tire tread chain consisting of an uninterrupted side having its termini merging into a pair of arcuate end portions, one of said end portions being materially larger than the other, said end portions facing each other, an inclined stem projecting from said larger end portion and extending in the same plane throughout and 95 an inclined stem projecting from the smaller end portion, and of greater length than the other stem and extending in the same plane throughout, said inclined stems forming the other side of the link.

In testimony whereof I affix my signature in the presence of two witnesses.

HARRY B. JACKSON.
